Application August 9, 1935, Serial No. 35,521

12 Claims.

(Cl. 221—79)

This invention relates to dispensers and more particularly to dispensers for tooth paste, shaving soap, creams and like products.

An object of the invention is to provide a 5 dispenser of this character which is of simple construction designed to receive loaded cartridges of the material to be ejected, which may be inserted and removed with ease.

A further object of the invention is to provide 10 a dispenser of rigid construction which is of attractive appearance and which will always maintain its shape.

A further object of the invention is to provide 15 a dispenser of this character from which the material may be ejected very readily, the dispenser being designed to be held and operated by one hand.

A still further object of the invention is to 20 provide a construction of attractive appearance, that is non-leaking and is of a sanitary character, all parts being washable.

A still further object of the invention is to 25 provide a construction in which the material ejected may be readily measured in the ejecting operation.

A still further object of the invention is to 30 provide a construction wherein the refill cartridge and casing co-operate to provide for ejection of the material to a full degree and eliminate seepage as between the casing and refill.

With these and other objects in view the invention consists essentially in an elongated container having a top provided with a closable dispensing opening, a main hollow body for receiving refill cartridges and ejecting means operable from the base of the container, the ejecting member being carried by the refill and being caused to move upwardly through the refill and container when operated so as to eject 40 the contents as required through the opening in the top. The operating means for the ejector is such as to permit operation by one hand with co-operating means to measure the quantity discharged, as well as means to prevent rotation of the ejecting mechanism in the wrong direction.

The container and refill are specially formed 50 so as to fit closely and to co-operate generally so as to avoid leakage and seepage of the material between the refill and the container. In addition, the ejecting member is formed to co-operate with said refill and container to this same end to associate with the cartridge in such a manner as to avoid rotary movement, as more fully described in the following specification and

illustrated in the accompanying drawings which form part of the same.

In the drawings:—

Figure 1 is a longitudinal section taken through the container illustrating a refill cartridge positioned therein and also illustrating the mounting of the various parts, including the ejecting mechanism.

Figure 2 is a fragmentary side elevation of the 10 top portion of the container.

Figure 3 is a side elevation of the cap.

Figure 4 is a fragmentary detail of the top 15 of the container over which the cap fits, illustrating the cut-out portion to co-operate with a projecting pin in the cap.

Figure 5 is an enlarged fragmentary section of 20 that portion of the base shown in the lower right hand corner of Figure 1.

Figure 6 is an enlarged detail section similar 25 to Figure 5 but taken through the base of the container at a different point.

Figure 7 is an enlarged fragmentary detail section of the base of the refill cartridge.

Figure 8 is a section taken on the line 8—8 of 30 Figure 7.

Figure 9 is a fragmentary perspective view of 35 the container carried in a hand illustrating the manner in which the ejecting mechanism may be operated by one hand.

Figure 10 is an enlarged plan view of the base 40 of the dispenser illustrating the form of the projecting mechanism operating member.

Figure 11 is an enlarged fragmentary section 45 taken through the base showing the mounting of the ejecting mechanism and operating means therefor.

Figure 12 is a plan view of the lower end of 50 the container with the base removed illustrating the serrations or grooving within the end of the container wall.

Figure 13 is an enlarged fragmentary detail of 55 the lower end portion of the container illustrating the serrations or cuts in the inner wall.

Figure 14 is an enlarged fragmentary perspective 60 of a portion of the base of the container illustrating the construction which co-operates with the ejecting operating member for measuring the quantity discharged and

Fig. 15 is a view of another member that functions 65 with the ejecting operating member for measuring the quantity of material discharged.

Figure 15a is another view of the ring member shown in Fig. 15.

Referring more particularly to the drawings, 70

Figure 1 is a general illustration in assembly of one form of construction my invention may take, A indicating the container as a whole, B the ejecting mechanism as a whole and C the ejector operating means. The container is preferably in the form of an elongated casing 10 of any suitable shape, illustrated in the present application as cylindrical. The container may have one end stepped as at 11 or curved or otherwise restricted 10 to terminate in the restricted nipple 12 provided with a suitable cap 13. The nipple 12 is preferably formed with a centrally disposed vertically extending dispensing channel or opening 14 which intersects an inclined channel 15, the latter 15 opening on the surface of the nipple to discharge the contents of the container when the ejecting mechanism B is operated. The cap is provided with a main orifice 16 which is of corresponding shape to the cross section of the channel 15 and is designed to register with this channel when the material in the container is to be dispensed, the cap being formed with an inwardly projecting rib or the like 17 which is spun thereon to engage with a suitable annular groove 18 20 formed around the nipple so that the cap may be rotated from one position to another, while being firmly held on the nipple against axial movement.

The nipple is preferably cut or otherwise 30 formed in one area with a relatively flat and vertically extending surface 19 which provides a recess defined by said surface and a shoulder 20, into which a pin 21 projecting within the interior 35 of the cap may extend, the shoulder 20 being preferably formed so as to slope upwardly to a slight extent from the point 22 midway between the outer defining edges of the recess to the outer defining edges so that when the pin 21 is disposed 40 at the central point 22 it is entirely free from engagement with the shoulder 20, but when it is moved to position a, the pin will bind on the surfaces of the shoulder, and likewise when it is moved to position b. Thus in these two positions 45 the cap is held firmly against rotational movement and must be dislodged by pressure. In the position a the opening 16 in the cap will register with the channel 15 in the nipple. In position b the opening 16 is moved completely out of registry with the channel 15 so that in use the cap is 50 held firmly in position during the ejecting of the paste, with the opening 16 positioned properly, and when it is being put away the cap is rotated to position b and the opening 16 moved to a closed position and held there to prevent air passing 55 into the interior of the container and thus affect the contents.

The interior of the container, which is of any desired cross section preferably circular is formed 60 with smooth walls and the upper end is preferably curved as at 23, although it may be sloped, or otherwise have its surface gradually narrowing towards the dispensing opening or discharge channel 14 to direct the material within the container towards this opening. The inner end of 65 the top of the container is extended as at 24 to project within the container, the channel 14 continuing through the extension 24 to open within the container a short distance below the upper extremity thereof, the extension being bevelled or sloped or otherwise of gradually narrowing character as at 25 to finally merge into the curved or gradually narrowing end wall 23 of the container, in effect following the contour of this 70 gradually narrowing wall and forming a co-oper-

ating guide for directing the material towards the dispensing opening.

The material is introduced to the container in a cartridge 26 which is constructed from any suitable material, preferably light transparent 5 material which is substantially rigid, although slightly flexible and is moisture proof. The cartridge is round at its upper end as at 27, or otherwise formed to coincide with the shape of the upper end of the container and it is orificed as at 10 28 to fit over the extension 24 of the container. In this respect it is pointed out that the bevelled or sloped portion of the extension is preferably an acute or sharp slope, so that upon removal 15 the cartridge will readily come away from the extension 24, and on the other hand when a new cartridge is inserted, it will fit upon the extension and snugly abut the curved wall of the container. Thus having regard to the extension and the manner in which the cartridge fits over 20 it in tight abutment with the curved wall of the container, it is apparent that this will provide means for eliminating seepage between the container and the cartridge refill.

Each cartridge is designed to carry ejecting 25 means for the material contained therein. The ejecting means takes the form of a screw threaded rod 29 upon which is mounted an ejector 30. These parts can be made very cheaply of light 30 aluminum for instance, and are designed to form a permanent part of the refill, and to be discarded when all the material has been ejected therefrom. The ejector 30 is formed with an upwardly curved surface 31, the central portion 35 of the upper surface being recessed as at 32 to coincide with the extension 24 at the top of the container.

Within the recess 32 projects a final ejector or discharge member 33 which surrounds the rod 29, the discharge member entering the passage 40 14 when the ejector has just about reached its upward extremity, so that any material in the neighborhood of the top of the refill will be discharged well up into the channel 14. Consequently, when one refill is removed, the interior 45 of the upper part of the container will be entirely clean with no sticky material therearound to contact with the next refill inserted, which might tend to hinder the removal of the refill after it had been positioned within the container 50 for a short time.

The lower portion of the ejector may be hollow as at 34 preferably for the sake of lightness of structure. It will be noted that the ejector 30 contacts firmly with the interior wall of the 55 refill and thus all material above the ejector will be moved upwardly within the refill. At the same time contact between the ejector and the refill wall form a means to prevent the ejector from turning. Thus, when the rod 29 is rotated the 60 ejector, held against rotation, will move readily upward within the refill.

The ejector may be made of rubber or other suitable material, my preferred construction being of aluminum. Ordinarily rubber or some 65 flexible material would be used to permit of firm engagement with the walls of the cartridge, but in view of the fact that the walls of the refill 26 are slightly flexible this will permit the use of hard material for the ejector and permit a 70 rather firm engagement as between the ejector and refill, even though the refill walls may not be absolutely true, inasmuch as the slight flexibility will compensate for any unevenness. The lower portion of the refill shell is formed to ac- 75

commodate the ejecting mechanism in a practical manner.

It will be noted on referring to Figs. 1, 5, 7, and 8 that I provide projecting shoulders 35 within the shell of the refill upon which a lower portion of the ejecting member 30 will sit as shown in Figure 1. The projecting shoulder is preferably pressed into the wall of the refill, that portion of the wall falling down from the shoulder being sloped as at 36 so that the ejector, once the rod is positioned within the refill, may be pushed upwardly into the refill and it will ride over the sloped surfaces finally lodging upon the projecting shoulder 35 which acts somewhat in the manner of the barb of a fishhook, preventing the ejector from being moved out of the refill again.

I form the lower edge of the refill with reinforcing members 37 spaced about its periphery, since the bottom portion of the refill is open to the greatest strain, the reinforcing members being formed by an increased thickness in the width of the wall to provide the desired amount of stiffening. At the same time these projecting reinforcements form a very convenient means for grasping the lower end of the refill in the inserting and removing operations. To accommodate these reinforcing projections the lower edge of the container wall may be notched as at 38 (see Fig. 13).

The refill cartridge 26 is held within the container by means of the container base 39. This may be made in any suitable form being preferably engageable with the container by means of the screw threading 40. The base assists in providing clamping means necessary to hold the cartridge firmly in position and also carries the operating means C for actuating the ejecting mechanism. The inner surface of the base is formed with an annular groove 41, on one side of which is a projecting annular flange 42 which is interiorly screw threaded to engage with the container, and on the other side an annular projection 43 extends formed with a sloped surface 44.

Upon referring to Fig. 1 and Figs. 5 and 6, it will be seen that the lower end of the refill cartridge 26 is positioned between the sloped surface 44 of the annular projection 43 and the interior wall of the container so that when the base is screwed tightly into position the sloped surface will have a wedging action upon the refill to clamp it very firmly against the lower interior wall of the container. This action combined with the notches or serrations 45 (see particularly Fig. 13) in the lower end of the container provides a very positive means for clamping the refill cartridge against rotational movement, and while the reinforcing projections 37 on the refill which engage within the notches 38 would also have a tendency to prevent rotational movement of the refill, the positive means provided relieve any strain that otherwise would be applied on the reinforcing members, which otherwise might be sheared from the refill.

The base 39 of the container is centrally orificed as at 46 to receive the projecting bushing 47 of the ejector operating means C. This may be projected through the opening 46 and secured rotatably therewithin by applying a small split washer or wire 48 between the interior wall of the base and a projecting shoulder on the bushing 47. On the outer portion of the base surrounding the orifice 46 the base is provided with an annular depressed or recessed portion 49

formed with a series of sloped surfaces 50 which terminate in suitable ratchet shoulders 51. These may vary in number, but there are preferably four equal surfaces 50.

The operating member C carries the split ring-like member 52 (see Fig. 15 particularly) which for instance is substantially the same as a split spring washer, one portion of which is bent downwardly as at 53 substantially at right angles to the part at which it is attached. On the other hand the projection 53 might constitute a separate piece attached to the ring like member 52. The projection 53 is designed to fit within a corresponding recess within the operating member C and the free upwardly projecting end 54 of the member 52 is designed to fit firmly against the sloped surfaces 50 in the base 39 so that when the operating member C is rotated in a clockwise direction, the end 54 of the ring like member will slide along one of the surfaces 50 until it reaches the shoulder 51 whereupon it will be dropped into engagement with the next and succeeding surface. As it drops it will make a light clicking noise, indicating the extent to which the operating member has been turned, and since there are four surfaces 50 of equal length the point at which the end 54 of member 52 disengages with each shoulder 51 will mark a quarter of a turn of the shaft 29. The screw threading of this shaft is so related to the ratchet construction that a quarter of a turn will provide the ejection of enough paste or material contained within the container for the purpose required, for instance for loading a toothbrush.

It will be noted that the lower end of the rod 29 is formed with a square face 55 which engages with a corresponding recess in the bushing 47, thus the rod will be positively rotated in accordance with the movement of the operating member C. Similarly the upper end of the rod 29 may be formed square or of any suitable cross section, it being restricted in width as indicated at 56 relatively to the cross sectional width of the rod so that when the ejector has been moved to its upward extremity, the screw threaded bore 45 will be positioned opposite to the plain reduced end portion, so that the rod 29 upon further rotation will just turn idly and the ejector will not be forced upwardly any further. It would otherwise tend to dam the operating parts of the device and possibly injure the operating structure.

The operating member C, it will be noted, takes the form of a rotatable member somewhat in the shape of a propeller blade, having in effect an arm projecting on each side of the axis of the rod 29 being formed with the gradually sloped surfaces 57 and the acutely sloped surfaces 58, or in other words surfaces at an acute angle to the base, these latter surfaces being positioned so that they will be directly opposite the thumb of one hand. The device, as illustrated in Fig. 9 will provide a firm means with which the thumb may engage to rotate the device in a clockwise direction. On the other hand, the gradually sloped surfaces 57 are positioned directly opposite to the surface 58 so that one cannot turn the device in an anti-clockwise direction, since the thumb would merely slip over the gradually sloping surface 57 without moving the operating member C. Thus the construction of the operating member C is such as to provide means for rotating the shaft 29 in one direction only. It is apparent therefore that once a refill is positioned within the container ready for use, the dispenser will operate efficiently and is proof against improper opera-

tion, which might cause injury to the working parts. The container wall may be slotted as at 59 adjacent its upper end to provide an indicating orifice which will clearly show when the container 5 is about empty.

An outstanding feature of the invention resides in the provision of a structure capable of being held and operated by one hand of the user. The container is grasped by the fingers or digits of one hand, as shown in Figure 9, and the operating member C is rotated by the thumb or a digit of the same hand. In this connection it will be noted that the base 39 is shown recessed or dished as at 39a, the operating member being of a depth 15 not greater than the recessed or dished portion, the latter gradually curving and terminating in a defining wall 39b. The dished or recessed base serves two purposes: It permits the container to stand upright without the operating member contacting with the support on which it has been placed and the gradually curved contour and defining wall 39b form a guide for the thumb or digit of the operator during the rotation of the operating member, providing for the smooth and 25 easy operation of the latter. In addition, the projecting stepped portion or flange construction 39c of the base provides a ready means for the digits of the operating hand to grasp and hold the container during operation.

Having regard to the foregoing, it will be apparent that I have provided a type of structure which may be manufactured very readily, since the main parts may be moulded throughout and require very little assembling work other than 30 the positioning of the operating member in rotational engagement with the base. The container may be made of a light and durable construction, and the refill with its carried projecting parts may be manufactured very easily and 35 very cheaply, so that the complete construction can be marketed in quantities at a comparatively low cost.

The refill provides a very handy means for the marketing of quantities of the material used and 40 as the refill is discarded after use and the container construction is such that it can be readily washed, it is apparent that the construction provides for a sanitary article of good appearance.

Other features that provide for a very desirable 45 construction reside in the provision of means for preventing the material from seeping between the refill cartridge and the container walls, the means for measuring quantities of the material as ejected and the simple means by which the 50 ejector may be operated by one hand, as clearly 55 illustrated in the drawings.

Various modifications may be made in this invention without departing from the spirit thereof or the scope of the claims, and therefore the 60 exact forms shown are to be taken as illustrative only and not in a limiting sense, and it is desired that only such limitations shall be placed thereon as are disclosed in the prior art or are set forth in the accompanying claims.

What I claim as my invention is:

1. A dispenser comprising an elongated container having a restricted dispensing opening at its upper end, a refill cartridge adapted to fit within the container and a base at the opposite 70 end of the container, means for retaining the refill cartridge against movement within the container, said refill cartridge being formed with a closed end having a centrally located opening therein, the end of said refill cartridge abutting the interior surface of the upper end of the con-

tainer, said opening in the refill cartridge registering with the restricted dispensing opening in the container, means for preventing seepage between the refill cartridge and container including an extension surrounding the dispensing opening and projecting from the upper end of the container into the interior thereof and through the opening in said refill cartridge, said extension joining with the end of the container, the defining edges of said opening in the refill cartridge fitting against the extension and the end of the container at their point of juncture, said refill cartridge carrying ejecting means including a screw threaded rod and an ejector having a screw threaded bore in engagement with said rod, said ejector being in frictional nonrotational engagement with said cartridge, means for retaining the ejecting mechanism within the cartridge, means carried by the base of the container connecting with the end of said rod in driving engagement and an operating member mounted on the base of the container connecting with said latter means for rotating said rod whereby upon rotation of said rod said ejector is caused to move upwardly ejecting material through the dispensing opening of the container.

2. The device as claimed in claim 1 in which the ejector is formed with a recess in its upper surface and a final ejecting member projecting upwardly within the recess, said recess being designed to surround the projecting extension, said final ejecting member designed to protrude into the dispensing opening when said ejector is moved to the upper end of the container.

3. The device as claimed in claim 1 in which the means for retaining the refill cartridge against movement within the container comprises an annular projection on the base of the container having a sloped surface projecting within the container and a gripping surface around the interior surface of the lower end of the container between which said refill cartridge is clamped when said base is normally positioned.

4. A dispenser comprising an elongated container having a restricted dispensing opening at one end and its opposite end open, a refill cartridge adapted to fit within the container having a closed end formed with a central opening adapted to abut the end of the container adjacent to the dispensing opening, said refill cartridge having its opposite end terminating adjacent to the open end of the container, a base for closing the open end of the container, means co-operating between the base of the container and said container for clamping the refill cartridge against movement when said base is in normal mounted position, said refill cartridge carrying ejecting means including a screw threaded rod and an ejector having a screw threaded bore in engagement with said rod, said ejector being in frictional non-rotational engagement with said cartridge, means for retaining the ejecting mechanism within the cartridge, means carried by the base of the container connecting with the end of said rod in driving engagement and an operating member mounted on the base of the container connecting with said latter means for rotating said rod whereby upon rotation of said rod said ejector is caused to move upwardly ejecting material through the dispensing opening of the container, said operating member being formed with at least one freely exposed arm at least one surface of which is at an acute angle to the base, said base being recessed to receive said operating member, the latter being of a depth not greater than the

depth of said recess, said operating member having at least one arm extending towards the edge of said recess, the latter having a defining wall adjacent to its edge forming a guide for a digit of the operator during rotation of said operating member whereby the latter may be operated by a digit of the hand holding the container to eject material through the dispensing opening.

5. The device as claimed in claim 4 in which the operating member is formed with two surfaces, the surface at an acute angle to the base being engageable by the digit of the operator to effect rotation of the operating member, and an opposed gradually sloped surface over which the 10 digit of the operator will slip whereby said operating member may be rotated only in one direction.

6. In a dispenser including an elongated container having a dispensing opening at one end 20 and a base closing the opposite end, a refill cartridge therefor comprising an elongated shell of light semi-rigid material closed at one end and open at its opposite end, said closed end having a centrally disposed opening adapted to co-operate with said container, ejecting means carried 25 within said cartridge to eject material carried therein through the central opening, said refill cartridge being provided with means to positively hold said ejecting means therein, including at least one projection stamped in the shell, said 30 projection having a sloped surface to permit the insertion of said ejecting means, said sloped surface terminating in a shoulder upon which an edge of said ejecting means abuts.

35. 7. In a dispenser including an elongated container having a dispensing opening at one end and a base closing the opposite end, a refill cartridge therefor comprising an elongated shell of light semi-rigid material closed at one end and open at its opposite end, said closed end having a centrally disposed opening adapted to co-operate 40 with said container opening, ejecting means carried within said cartridge to eject material carried therein through the central opening, said refill cartridge being provided with means to positively 45 hold said ejecting means therein, a portion of said shell at its open end being flared between the base and the container for clamping therebetween to hold said shell against movement.

50. 8. A dispenser comprising an elongated container having a restricted dispensing opening at its upper end, a refill cartridge adapted to fit within the container, ejecting means including a movable ejector positioned within the refill and 55 container, a base at the lower end of the container and operating means mounted on the base for operating the ejecting means, the upper end of the container having an interior surface gradually narrowing towards the dispensing opening, an annular member surrounding the dispensing opening and projecting within the container from its upper end, said member gradually narrowing towards its lower end and having an exterior surface following the contour of the upper 60 end of the container, one end of said refill cartridge having a contour coinciding with the

upper end of said container, being designed to abut the latter and formed with an opening adapted to register with the dispensing opening, said annular member projecting through the opening in the refill cartridge, the interior surface of said end of the refill cartridge and the exterior surface of said annular member forming a guide to the dispensing opening for material carried within said cartridge, said ejector having a recess to co-operate with said annular projecting member, the defining walls of said recess co-operating with said graduating surface of the refill and extension to eject substantially all material from the refill.

9. In and for a dispenser, a refill cartridge 15 comprising an elongated flexible tubular shell designed to carry material to be dispensed, said member having a restricted end formed with an opening therein, said end gradually narrowing towards said opening, the opposite end being open 20 and flared outwardly, and having a series of inwardly directed projections stamped in the shell and a series of outwardly directed projections circumferentially spaced around the shell adjacent to the open end.

10. In and for a dispenser, an elongated hollow shell having flexible walls designed to carry material to be dispensed, said shell being restricted at one end and provided with an opening therein, said end gradually narrowing towards said opening, the opposite end of said shell being open, a closure member for the open end in the form of an ejector positioned within the shell, said ejector being rigid in construction and disposed in pressure engagement with the flexible 30 walls of the shell, said walls being formed with a projection extending within the shell, said projection having a sloped surface to permit insertion of said ejector, the sloped surface terminating in a shoulder to retain said ejector within 35 the shell.

11. In and for a dispenser, a refill cartridge comprising an elongated flexible tubular shell designed to carry material to be dispensed, said member having a restricted end formed with an opening therein, said end gradually narrowing towards said opening, the opposite end being open and flared outwardly, and said shell having an internal laterally projecting portion stamped therein adjacent to and inwardly of its flared 45 open end.

12. In and for a dispenser, an elongated hollow shell having flexible walls designed to carry material to be dispensed, said shell being restricted at one end and provided with an opening therein, said end gradually narrowing towards said opening, the opposite end of said shell being open, a closure member for the open end in the form of an ejector positioned within the shell, said ejector being rigid in construction and disposed in pressure engagement with the flexible walls of the shell, said walls being formed with a projection extending laterally within the shell inwardly of its open end into the path of the ejector whereby to retain ejector within the shell.

GARNET ADAM MAGUIRE.
